MOLD FOR FORMING FINGERNAILS

Arthur Fink, New York, N. Y., assignor to Artel Cosmetics, Inc., New York, N. Y., a corporation of New York

Application April 4, 1955, Serial No. 35,336

Term of patent 14 years

(Cl. D86—10)

Fig. 1 is a perspective view of a mold for forming fingernails, showing my new design.

Fig. 2 is a top plan view on a reduced scale.

Fig. 3 is a cross-sectional view along line 3—3 of Fig. 2.

The design comprises a generally tubular body, open at both ends, having its front edge sloping back from top to bottom in a relatively flat ogee form of curve, having its middle and rear top portions cut out, and having its rear bottom portion cut out, so as to provide a pair of spaced, separate side wings which extend rearwardly from a top front bridging portion and are connected by a bottom intermediate bridging portion.

I claim:

The ornamental design for a mold for forming fingernails, substantially as shown and described.
